TEAR STRIP APPLYING MECHANISM FOR
GUM STICK WRAPPING MACHINES

Willet B. Ranney, Chicago, Ill., and Albert F. Ruhf, Cos Cob, Conn., assignors to Wm. Wrigley Jr. Company, Chicago, Ill., a corporation of Delaware

Original application April 1, 1940, Serial No. 327,262. Divided and this application February 17, 1943, Serial No. 476,174

8 Claims. (Cl. 93—1)

This invention relates to an improvement in gum stick wrapping machines and consists of the matters hereinafter described and more particularly pointed out in the appended claims.

More specifically the invention relates to an automatic machine for wrapping and sealing single sticks in wrappers severed from a continuously fed wrapper-forming web wider than the sticks, having on its bottom surface display panels for the top and bottom of a wrapper spaced at predetermined lateral and longitudinal intervals, by depositing sticks on said web at like longitudinal intervals in register with the display panels to appear on the bottom of the wrapper, then folding said web laterally and sealing it to form a flat, continuous tube presenting the top panels in register with the tops of the sticks, thereafter severing said tube into wrapper lengths with like tubular end projections, and then sealing and folding said projections upon themselves and closing them against the ends of the enclosed sticks.

In order to open a wrapped stick of the kind, it is preferable to apply transversely to the wrapper-forming web a tear strip. This tear strip is applied to the web at equal distances apart and extends transversely thereof. It also projects slightly at one edge.

The object of the invention is to provide in such a machine a mechanism for severing tearing strips from a continuously fed web and applying and sealing them at predetermined intervals to the advancing wrapper-forming web in position to tear the sealed wrapper transversely to remove the stick.

This application is a division of our application filed April 1, 1940, Serial No. 327,262, for Gum stick wrapping machine.

In the drawings:

Figure 1 is a partial front elevation showing the feed end of a machine of the kind described, and the tearing strip, feeding, cutting and gluing devices for applying the tearing strip to the forwardly moving wrapper-forming web.

Figure 2 is a perspective view of the tearing strip severed and spot-glued as when applied to the wrapper web.

Figure 3 is a section through Figure 1 in planes indicated by the broken line 3—3 of Figure 1.

Figure 4 is a section in a plane indicated by the line 4—4 of Figure 3.

Figure 5 is a fragmentary section in a vertical plane of the parts enclosed in Figure 4 by the dotted circle 4a.

Figure 6 is a section through Figure 1 in a plane indicated by the line 6—6 of Figure 1.

Figure 7 is a diagrammatic view of the feeding, cutting, gluing and strip mechanism for severing and gluing the tearing strip to the wrapper strip.

Figure 8 is a partial perspective view of some of the parts shown diagrammatically in Figure 7.

Figure 9 is a partial perspective view of the stripper belt, tearing strip and wrapper-forming web with a tearing strip applied to said wrapper web.

Figure 10 is a fragmentary view on an enlarged scale, partly in section and partly in front elevation, in the vertical plane of one of the stripper belts including the pulleys for said belts and a speed-control mechanism therefor.

Figure 11 is a partial horizontal section through Figure 10 in a plane indicated by the line 11—11 of Figure 10.

Figure 12 is a vertical sectional view on an enlarged scale in a plane indicated by the line 12—12 of Figure 10.

Figure 13 is a plan section of the part shown in Figure 12 indicated by the line 13—13 of Figure 12.

Figure 14 is a view partially in section and partially in elevation on an enlarged scale in a plane indicated by the line 14—14 of Figure 13.

Referring now to that embodiment of the invention shown in the drawings: 15 indicates the left-hand feed end of a wrapping machine for wrapping and sealing single sticks of the kind hereinbefore described. 16 indicates a drum about which is fed an endless, horizontally disposed feed belt 17, the other end of said belt being supported by a similar drum (not shown). The drum 16 rotates clockwise, as indicated by the arrow shown thereon in Figure 1, so that the upper lap of the belt advances from the left or loading end of the machine toward the right or finishing end (not shown).

18 indicates the wrapper-forming web which is drawn from a spool (not shown) in a familiar manner. Said web passes about the drum 16 in contact with the top lap of the feed belt 17 toward the right. The web is wider than the sticks to be wrapped, and in the operation of the wrapping machine it is folded laterally and sealed about the sticks to form a flat, continuous tube which is thereafter severed into wrapper lengths, and the flat tubular ends thereof are folded upon themselves and sealed against the ends of the sticks.

The mechanism for applying the tear strips to the advancing stick wrapper-forming web is

mounted on an upright housing 19 fixed to the frame 15. The tear strips are severed in succession from a web 20 wider than the wrapper-forming web 18, taken from a supply roll 21 mounted on a spindle 22 attached to the housing 19. Said web is fed about tension rolls to a feed roll 24 (see Figures 1 and 6) with which it is held in contact by a tension roll 25 mounted on a spring-controlled arm 26 pivoted on the housing. From the feed roll 24 the web passes loosely between idle rolls 27 and thence between feed rolls 28, 29. One of said rolls 29 carries spring-loaded gripper blades 30, spaced at equal distances about the roll and projecting slightly beyond its surface to grip the web 20 against the roll 28.

31 indicates a transfer roll, which is engaged by a cutting roll 32. Said cutting roll carries equally spaced spring-loaded, radially projecting cutting blades 32^a which are adapted to engage the transfer roll. Said transfer roll is provided with shearing inserts 33 (see Figure 5) set into its surface at points adapted to be engaged by the cutting blades 32^a in the rotation of the two rolls. The transfer roll 31 is provided adjacent the inserts 33, 33 on the leading side with suction ports 34 connected to air ducts 35 extending parallel to the axis of the roll. Said ducts register with and open into an arcuate port 36 in a plate 36^a (see Figure 3) against which the end of the roll 31 has wiping engagement and which is connected to an exhaust pipe 37 (see Figure 1) by a duct 37^a registering with said port. Said arcuate port 36 bridges two of the ducts 35 and extends nearly to a third duct 35 as shown in Figure 4.

The transfer roll 31 is engaged by a second transfer roll 38 which contacts the wrapper-forming web 18. It contains within it means forming fixed, laterally spaced discs 41 disposed eccentrically of and below the axis of rotation of said transfer roll. Upon said discs are rotatively mounted pulley rings 42 for endless strip-per cords 43 which are adapted to disengage the severed tear strips from said second transfer roll and deposit it on the web 18, as shown in Figure 4.

The second transfer roll 38 is provided with suction ports 39 opening through its surface at points spaced at distances equal to the distances of the suction ports on the transfer roll 31, but has an additional port because of its larger diameter. Said ports are connected by suitable ducts to an exhaust pipe 38^a in a manner similar to that described in the case of the transfer roll 31 and illustrated in Figures 3 and 4.

The second transfer roll 38 is comprised of three laterally spaced sections fixed on a horizontal shaft 40 (see Figures 3 and 11). Intermediate said sections are the laterally spaced discs 41 which provide bearing for grooved pulley rings 42, 42 about which pass cord belts 43, 43 (see Figures 4 to 11, inclusive). The other ends of said belts are connected to grooved driving pulleys 44 (see Figure 10). The construction described and shown provides annular spaces opening through the periphery of the transfer roll 38 in the plane of and about the grooved rings 42 for the entrance of the cord belts 43 and also for the introduction of bracket arms 38^m which are fixed to the eccentrically mounted discs 41 and attached to the near face of the housing 23. This prevents the rotation of said eccentric discs 41 but permits the grooved rings 42 to rotate thereon.

The center of rotation of the grooved pulleys 75

is so disposed that the bottom laps of the cord belts 43 will come into contact with the wrapper-forming web 18 when a tear strip has been applied transversely thereto and has been brought to position as shown in Figure 10 at 20^x. At this position the cords 43 traveling in contact with the web 18 will disengage said strip from the second transfer roll 38 by reason of the fact that the surface of the roll continues in a circular path rising above the level of the cords which travel with and at the same speed as the wrapper-forming web 18. The operation of this mechanism is clearly illustrated in the diagrammatic views, Figures 7 to 9, inclusive.

15 The transfer roll 38 is mounted on a horizontal shaft 40 (see Figures 1 and 3), and the transfer roll 31 and the cutter roll 32 are mounted respectively on horizontal shafts 31^x and 32^x. Said shafts are connected respectively by gears 40^x, 31^x and 32^x. By this means the cutter roll 32, the first transfer roll 31 and the second transfer roll 38 are geared to rotate in unison at the same peripheral speed in the directions indicated respectively by the arrows applied to said rolls in Figure 1. Said shaft 40 carries a sprocket 46 driven by a sprocket chain 46^a. The feed roll 24 (see Figures 1 and 6) is mounted on a horizontal shaft 24^x, and the feed roll 28 is mounted on a horizontal shaft 28^x. The gear 40^x meshes with the gear 31^x of the first transfer roll 31, which in turn meshes with a pinion 48^x on a horizontal countershaft 48. The pinion 48^x engages and drives a gear 28^x on the shaft 28^x of the feed roll 28. Said gear 28^x engages and drives a gear 29^x fixed on the shaft 29^x of the feed roll 29. A gear 24^x is mounted on the shaft 24^x of the feed roll 24. Said gear is driven by intermediate gearing 49^x, 28^x and 28^x. The countershaft 48 is connected by sprockets and chain 50 to a horizontal shaft 51 which projects forward from the face of the housing 19 into a glue-pot 52 wherein it has fixed to it a glue roll 52^a. Associated with said roll is a rotary glue paddle 53 fixed upon a horizontal shaft 54 in position to transfer glue from the glue roll 52^a to the tear strip 20^x in spots 20^y, as indicated in Figure 2. Said shaft 54 has fixed to it a gear 54^a which is engaged and driven by gear 55 mounted on the shaft 51. (See Figure 6.)

50 Referring now briefly to the operation of the mechanism above described for severing a strip from the tear strip web 20: Said web is fed continuously by the feed roll 24 to the rolls 28, 29 by which it is intermittently fed, there being an excess feed from the roll 24 to the feed rolls 28 and 29 as indicated by the loop 20^x shown in Figure 1.

55 The rolls 28 and 29 rotate continuously. But the blades 30 carried thereby are brought to engagement with the web 20 intermittently to feed the web 20 a distance equal to the predetermined width of the tear strip 20^x. Similarly the cutter blades of the cutter roll 32 come to engage the shearing inserts 31^a of the transfer roll 31 at successive intervals equal to those of the feed roll 29. And the intervals are coincident with the intervals of operation of the roll 29. As a result, the width of strip fed by the feed rolls 28 and 29 is severed by the cutter roll blades 32^a.

60 As the tear strip is sheared from the web 20 it is subjected to the pull at the suction port 34 and held to the surface of the transfer roll 31. In the continuous rotation of the transfer roll 31 the said tear strip is retained on said roll until said strip is brought to engagement with

the second transfer roll 38. As this time the vacuum exerted at the suction port 34 through arcuate port 36 and duct 35 is broken. A suction port 39 in the second transfer roll 38 picks up said tear strip and carries it until it is brought to position in engagement with the top of the wrapper web 18, when the vacuum is broken. At that point the tear strip is stripped from the transfer roll as hereinbefore described, and deposited upon the web 18.

Prior to the deposit of the tear strip on said web 18, as it is carried about by the transfer roll 38, spots of glue 20^y are deposited on the tear strip by the glue paddle 53. The glue spots are spaced on the tear strip as are the cords 43, so that said cords will engage the strips above said glue spots and will hold said strips to the web until the glue is set.

The sprocket chain 46^a which drives the shaft 40 of the secondary transfer roll 38 for the tear strip is operatively connected by any suitable mechanism, as for example by that shown in the application of which this is a division, to a power shaft in such manner as to drive said shaft 40 in timed relation to the feed of the web 18. The grooved driving pulley 44 for the cord belts 43 are also operably connected with suitable driving mechanism, as for example by that shown in the application of which this is a division, so as to drive said belts in timed relation to the feed of said web 18, as hereinbefore described.

We claim as our invention:

1. In combination, means for advancing a wrapper-forming web, means for advancing a tear-strip-forming-web of a width equal to the required length of said tear strips, cutter means including a transfer roll for intermittently severing said second web transversely into tearing strips, a second transfer roll intermediate said first transfer roll and said wrapper-web, said transfer rolls being constructed to transfer said tearing strips successively and in predetermined spaced relation from said cutter and apply them to said wrapper-web, and means for stripping said tearing strips from said second transfer roll and for holding them against said wrapper-web.

2. In combination, means for advancing a wrapper-forming web, means for advancing a tear-strip-forming-web of a width equal to the required length of said tear strips, cutter means including a transfer roll for intermittently severing said second web transversely into tearing strips, means for applying adhesive to said strips, a second transfer roll intermediate said first transfer roll and said wrapper-web, said transfer rolls being constructed to transfer said tearing strips successively and in predetermined spaced relation from said cutter and apply it to said wrapper-web, and means for stripping said tearing strips from said second transfer roll and for holding them against said wrapper-web until said adhesive is set.

3. In combination, means for advancing a wrapper-forming web, means for advancing a tear-strip-forming-web of a width equal to the required length of said tear strips, coacting feed rolls adapted to advance said second web a distance equal to the designed width of said tearing strips, coacting cutter and transfer rolls adapted to sever a tearing strip which is picked up and advanced by said transfer roll, a second transfer roll engaging on one side said first transfer roll and on its other side said wrapper-web, said second transfer roll being provided with spaced parallel transverse grooves, means providing non-

rotatable eccentrically disposed discs in the planes of said grooves, rotative rings on said discs, endless parallel strip cords mounted on said rings with their bottom laps advancing on said wrapper-web, and driving pulleys engaged with said strip cords.

4. In combination, means for advancing a wrapper-forming web, means for advancing a tear-strip-forming-web of a width equal to the required length of said tear strips, coacting feed rolls adapted to advance said second web a distance equal to the designed width of said tearing strips, coacting cutter and transfer rolls adapted to sever a tearing strip which is picked up and advanced by said transfer roll, a second transfer roll engaging on one side said first transfer roll and on its other side said wrapper-web, means for applying adhesive to said strips as they are advanced by said second transfer roll, said second transfer roll being provided with spaced parallel transverse grooves, means providing non-rotatable, eccentrically disposed discs in the planes of said grooves, rotative rings on said discs, endless parallel strip cords mounted on said rings with their bottom laps advancing on said wrapper-web, and driving pulleys engaged with said strip cords.

5. In combination, means for advancing a wrapper-forming web, means for advancing a tear-strip-forming-web of a width equal to the required length of said tear strips, a cutter roll provided with annularly spaced radial blades extending transversely of said second web, a transfer roll having similarly spaced shearing inserts coacting with said cutter blades and provided with adjacent suction ports to pick said strips from said cutter roll, a second transfer roll engaged with the first named transfer roll on one side and with said wrapper-web on its other side provided with like annularly spaced suction ports to pick said strips from said first transfer roll, and means for exhausting air from the ports of said two transfer rolls in timed relation such that the tear strips are picked up by the first, transferred to the second, and released by the second when in contact with said wrapper-web.

6. In combination, means for advancing a wrapper-forming web, means for advancing a tear-strip forming web of a width equal to the required length of said tear-strips, cutter means for intermittently severing said second web transversely into tearing strips, and means for transferring said severed tear-strips from said cutter means and applying them in predetermined spaced relation on said wrapper web, and transversely of the latter.

7. In combination, means for advancing a wrapper-forming web, means for advancing a tear-strip forming web of a width equal to the required length of said tear-strips, cutter means for intermittently severing said second web transversely into tearing strips, and means for transferring said severed tear-strips from said cutter means and applying them in predetermined spaced relation on said wrapper web, and transversely of the latter, including a transfer roll having gripping means rotating at the same peripheral speed as the rate of advance of said wrapper web.

8. In combination, means for advancing a wrapper-forming web, means for advancing a tear-strip forming web of a width equal to the required length of said tear-strips, cutter means for intermittently severing said second web

transversely into tearing strips, and means for transferring said severed tear-strips from said cutter means and applying them in predetermined spaced relation on said wrapper web, and transversely of the latter, including a transfer roll having gripping means rotating at the same peripheral speed as the rate of advance of said

5 wrapper web, means for applying adhesive to said strips while gripped on said transfer roll, and means for stripping said tearing strips from said transfer roll and holding them against said wrapper web until the adhesive is set.
